UNITED STATES PATENT OFFICE.

JACOB HIRSHFELD, OF NEW YORK, N. Y.

BAG.

No. 800,302.

Specification of Letters Patent.

Patented Sept. 26, 1905.

Application filed June 23, 1905. Serial No. 266,613.

To all whom it may concern:

Be it known that I, JACOB HIRSHFELD, a citizen of the United States, and a resident of the borough of Manhattan, in the city and State of New York, have invented a new and useful Improvement in Bags, of which the following is a specification.

This invention relates to certain improvements in bags, and particularly to that class known as "opera-bags."

The object of my invention is to provide certain improvements in bag-closures whereby side plates are provided at the mouth of the bag, which side plates are used in connection with hand-cords for opening and closing the mouth of the bag.

A practical embodiment of the invention is represented in the accompanying drawings, in which—

20 Figure 1 is a perspective view of a bag having my invention applied thereto, the mouth of the bag being represented as partially open; and Fig. 2 is a face view of one of the side plates.

25 The body of the bag is denoted by 1 and may be of any desired shape, style, and material. I provide the bag with side plates 2 at its mouth, each of which side plates is provided along its upper edge with a series of 30 holes 3. The upper edge of each side plate is also scalloped, the recesses 4 being located intermediate the holes 3 and the projections 5 being located above the holes. The ends of 35 each side plate are provided with transversely- elongated holes 6 and 7.

The hand-cords of the bag comprise portions 8 and 9, which are laced over the upper edges of the side plates 2, and portions 10 and 11, which are used for drawing the plates together to close the mouth of the bag. These 40 cords may be made in one piece or in several pieces, as found most convenient. The ends of the mouth between the side plates 2 are

preferably finished with sections 12 and 13 of the cord to produce a finished appearance. 45

The portions 8 and 9 of the hand-cords are located within the recesses 4 as they pass over the upper edges of the side plates and are thus held the required distance apart to produce a finished appearance along the sides 50 of the mouth of the bag. The bag itself is secured in any well-known and approved manner to those portions 8 and 9 of the cord— as, for instance, by stitching it thereto.

The portion 10 of the hand-cords is secured 55 to the mouth of the bag exterior to one of the side plates. It then extends through the holes at the ends of that particular side plate and from thence passes through the holes in the ends of the other side plates. Similarly, 60 the portion 11 of the hand-cords is attached to the opposite side of the mouth from the portion 10 and first passes through the holes in the ends of its adjacent side plate and from thence through the holes in the opposite side 65 plate. It will thus be seen that the strain of closing the bag by drawing the side plates together is all brought upon the side plates.

What I claim as my invention is—

1. A bag provided with side plates at its 70 mouth having holes along their upper edges and at their ends and hand-cords laced through the said holes.

2. A bag provided with side plates at its mouth having scalloped upper edges and holes 75 along said upper edges and hand-cords laced over the upper edges of the plates and through the said holes.

In testimony that I claim the foregoing as my invention I have signed my name, in presence of two witnesses, this 22d day of June, 1905.

JACOB HIRSHFELD.

Witnesses:

FREDK. HAYNES,
HENRY THIEME.
